Specification for Design.

Patented Jan. 17, 1922.

Application filed February 25, 1921. Serial No. 447,884. Term of patent 14 years.

To all whom it may concern:

Be it known that I, WILLIAM ANTON SCHULER, a citizen of the United States, and resident of New York, in the county of New York and State of New York, have invented a new, original, and ornamental Design for a Fastener for Key Rings, Chains, Necklaces, and Similar Articles, of which the following is a specification, reference being had therein to the accompanying drawing, forming part thereof.

The figure is a plan view of a fastener, showing my new design.

I claim:

The ornamental design for a fastener for key rings, chains, necklaces, and similar articles, as shown.

In testimony whereof I hereunto affix my signature.

WILLIAM ANTON SCHULER.
